UNITED STATES PATENT OFFICE.

FREDERICK S. DENISON, OF MINNEAPOLIS, MINNESOTA, ASSIGNOR TO MINNEAPOLIS
HEAT REGULATOR CO., OF MINNEAPOLIS, MINNESOTA, A CORPORATION.

THERMOSTAT.

1,282,546.

Specification of Letters Patent. Patented Oct. 22, 1918.

Application filed January 3, 1916. Serial No. 69,865.

To all whom it may concern:

Be it known that I, FREDERICK S. DENISON, citizen of the United States, resident of Minneapolis, county of Hennepin, State of Minnesota, have invented certain new and useful Improvements in Thermostats, of which the following is a specification.

The cover or guard mounted on the base of a thermostat to conceal and protect the 10 thermostatic bar has generally been secured by means of screws tapped into the wall of the base. A considerable time has been required for inserting and removing these screws and often the screws are lost or misplaced when the user of the thermostat attempts to obtain access to the bar.

The object, therefore, of my invention is to provide a means for mounting this cover which will permit its quick and convenient 20 removal from the thermostatic base and remounting thereon.

The invention consists generally in various constructions and combinations, all as hereinafter described and particularly pointed 25 out in the claim.

In the accompanying drawings forming part of this specification,

Figure 1 is a front view of a thermostat with a guard embodying my invention 30 mounted thereon,

Fig. 2 is a plan view of the guard, being partially broken away,

Fig. 3 is an enlarged detail view, showing the manner of mounting the guard on the 35 base of the thermostat,

In the drawing, 2 represents the base of the thermostat and 3 a time piece mounted thereon and 4 the guard which covers and conceals the thermostatic bar, as usual in devices of this kind. Generally this cover has been secured to the base by means of screws and considerable time is required for removing and inserting them, and as the screws are comparatively small, they are frequently lost when removed, particularly if the work 45 is being done by the owner of the thermostat.

Access to the thermostatic bar is sometimes necessary and to avoid the inconvenience and 50 delay incident to the usual fastening means

I provide slots 5 in the outer wall of the base, preferably near the edges thereof and upon the side walls 6 of the cover, made of comparatively thin sheet metal, I form lugs 7, curved slightly and adapted to slip into the 55 slots 5, the spring of the metal being sufficient to allow the walls to be pressed inwardly until the lugs will enter the slots and then, when the walls are released, they will spring outwardly to engage the lugs with 60 the outer walls of the slots, as shown in Fig. 3, and thereby lock the cover in place on the base.

The lugs are so mounted on the cover that the edges of the cover walls, when the device is in use, will lap by the outer edges of the slots and entirely conceal them, so that a person standing in front of the base or at the side thereof would not be able to distinguish any means for fastening the cover on 70 the base, or any fastening means for the cover.

To remove the cover from the base, it is only necessary to compress the side walls sufficiently to disengage the lugs from the 75 slots.

In various ways the details of construction herein shown and described may be modified and still be within the scope of my 80 invention.

I claim as my invention:

In combination with a thermostatic base having front and side walls and slots formed in said front wall adjacent said side walls, a cover fitting said base and having side walls 85 of spring material provided on their longitudinal edges with curved lugs which are adapted to enter said slots and engage the outer edges thereof, the tension of said cover walls holding said lugs in engagement with 90 said edges, said slots being of sufficient width to allow the disengagement of said lugs from said edges for the removal of said cover.

In witness whereof, I have hereunto set 95 my hand this 30th day of December 1915.

FREDERICK S. DENISON.
